CLAIM

The ornamental design for a hoist for riding mowers, as
shown and described.

DESCRIPTION

FIG. 1 is a front and left side perspective view of a hoist
for riding mowers showing my new design;

FIG. 2 is a side elevational view thereof with the oppo-
site side being a mirror image thereof;

FIG. 3 is a top plan view thereof;

FIG. 4 is a bottom plan view thereof;

FIG. 5 is a front elevational view thereof; and,

FIG. 6 is a rear elevational view thereof.

The broken line showing of a riding mower is for illus-
trative purposes only and forms no part of the claimed
design.
